UNITED STATES PATENT OFFICE.

GEORGE C. YOCUM, OF SCRANTON, PENNSYLVANIA.

VENDING-MACHINE.

No. 876,126.

Specification of Letters Patent.

Patented Jan. 7, 1908.

Application filed August 30, 1906. Serial No. 332,699.

To all whom it may concern:

Be it known that I, GEORGE C. YOCUM, a citizen of the United States, residing at Scranton, in the county of Lackawanna and State of Pennsylvania, have invented certain new and useful Improvements in Vending-Machines, of which the following is a specification.

This invention relates to a motor driven vending machine, in which the motor which actuates the delivery mechanism may be operated to deliver one or more articles, depending upon the value of the coin inserted in the machine.

In the accompanying drawings I have illustrated my invention in connection with a machine for feeding and cutting off tickets from a ticket strip, the machine there shown being designed particularly for vending soda water and other checks or tickets which are to be exchanged by the purchaser for drinks.

The construction, operation and advantages of my improved vending mechanism will be clear from the following specification, taken in connection with the accompanying drawings, in which.

Figure 1 is a plan view of the vending machine, with the cover and coin chutes removed, the front of the casing being shown in section and part of the top supporting plate of the motor being broken away; Fig. 2 is a front elevation of the coin operating mechanism, with the parts in normal positions; Fig. 3 is a similar view showing the position of the parts shortly after the machine has commenced to operate; Fig. 4 is a similar view showing the positions of the parts after the shaft carrying the cam wheels has nearly completed a revolution; Fig. 5 is a section on the line 5—5 of Fig. 4, showing the levers for stopping and releasing the motor in plan view; Fig. 6 is a section on the line 6—6 of Fig. 2, the main operating gear of the motor being omitted, parts being shown in their normal positions; Fig. 7 is a side elevation of the coin operating mechanism, taken at the right hand side of Fig. 4, the coin receptacle being partly broken away and the slide for retaining coins in the primary compartment of the receptacle being raised to permit the coin to move into the secondary compartment; Fig. 8 is a section on the line 8—8 of Fig. 3; Fig. 9 is a side elevation of the governing fan and the detent for releasing and engaging the same, and Fig.

10 is a section through the coin receptacle on the line 10—10 in Fig. 6.

Referring to Fig. 1 of the drawing, A indicates the casing of a vending machine, with the top removed and the front part of the 60 casing shown in horizontal section. Within the casing is arranged the spring motor M, which actuates a pair of feed rolls 1 for intermittently feeding forward a paper ticket strip 2, and also a rotary knife 3 which cuts 65 off tickets from the strip when the feeding movement ceases in the manner hereinafter described. The motor has a main operating gear 4, connected, as shown in the various figures of the drawing, by a train of gearing 70 5, 6, 7, 8, 9, 10 and 11 to a shaft 12 having a fan 13 thereon for governing the speed of the motor. The train of gearing is suitably mounted upon shafts having bearings in upper and lower plates 14 and 15. The 75 shaft 16 has at its upper end a crank 17, and a link 18 connects this crank with a lever 19. One end of the lever 19 is pivoted at 20 to one side of the motor frame, and the opposite end of the lever is connected by a link 21 80 to an arm 22 of a clutch or ratchet 23 on the feed wheel shaft 24. Each rotation of the crank 17 causes the lever 19 to oscillate about its pivotal point from the normal position, shown in full lines, in Fig. 1, to the position 85 shown in dotted lines, and back. During the movement of the lever from normal position, the clutch 23 does not rotate the feed wheels, but during the return movement to normal position the clutch engages the feed 90 wheel shaft and rotates the feed wheels, the latter thus feeding forward a ticket onto an inclined platform or chute 25 which leads to an opening 25^a in the front of the casing. This feeding movement, as stated, occurs 95 during the last half turn of the crank 17, and just before the motor comes to a stop, as hereinafter explained, so that when the motor is again started a piece of the paper strip equal to the length of the ticket will rest upon the platform 25, ready to be cut off by the rotary knife 3 when the motor is again started into operation. This knife is mounted upon a shaft 26 which is connected by gears 27, 28 and 29 to the main operating 100 gear 4, and is normally held in position to commence cutting off the ticket when the motor is started. The knife makes one rotation for each oscillation of the lever 19. When the motor starts into operation, and 105

while the lever 19 is moving from the normal position to the position indicated in dotted lines in Fig. 1, the feed wheels and strip then being stationary, the knife cuts off the previously fed ticket, which slides down a platform 25, and out of the machine through the opening 25^a in the casing. While the knife is making the second half of its revolution after cutting off the ticket the oscillating lever returns to its normal position and causes the feed wheels to move and feed forward another ticket onto the shelf or platform 25, ready to be cut off at the next rotation of the knife.

15 The shaft 31 to which the main operating gear and the motor spring are connected, is provided with a ratchet or clutch arm 32, having a socket 33 therein to receive the end of a rod or key which is to be inserted 20 through a horizontal slot in the side of the casing for the purpose of winding the motor. A suitable recording device R is operated by a tooth 18^a on the link 18, to record the number of tickets fed and cut off. I provide 25 means for automatically releasing the motor when a coin of the value of a ticket is placed in the machine, and for automatically stopping the motor after a single ticket has been cut off and another ticket has been fed forward; or if a coin having the value of several 30 tickets is inserted in the machine a corresponding number of tickets will be cut off and fed forward before the machine comes to a stop.

35 A coin receptacle C is suitably secured to the top plate of the motor by a standard 34. This receptacle as shown in Figs. 6, 7 and 10 consists of a narrow trough having sides 35 and 36 fitting closely against the sides of a 40 coin balance D, which latter is pivoted near the top and at one end of the receptacle in ears or brackets 37, and has a weight 38 at one end which holds the balance normally in horizontal position, as shown in Fig. 6, 45 and in dotted lines in Fig. 7. The coin balance is connected by a link 39 to one end of a detent 40, which latter is pivoted at a point intermediate its ends upon a suitable support 41. The opposite end of the detent 50 engages the fan 13, as shown in Figs. 2, 5, 6 and 9, and prevents operation of the motor as long as the coin balance is in horizontal position. When, however, the coin balance is tilted by a coin into the position 55 shown in dotted lines in Fig. 6 and in full lines in Fig. 7, the detent 40 is thereby rocked out of engagement with the fan as shown in Figs. 7 and 8, and in dotted lines in Fig. 9 and the motor is thus permitted to 60 operate until the coin balance and detent return to their normal positions. After the coin balance has been tilted out of the normal position by the weight of a coin placed on the balance, and the detent thereby 65 moved out of engagement with the fan to

release the motor, the detent and coin balance cannot return to their normal positions to stop the motor until one ticket has been cut off by the knife 3 and another ticket has been fed forward into position to be cut off. 70 This is accomplished by an interposing or locking lever 42 (see Figs. 5 and 8) pivoted at 43 to the lower plate 15 of the motor frame and movable by a cam wheel 44 in one direction and in the opposite direction by a 75 spring 45. The cam wheel 44 is mounted upon the lower part of the shaft 16, as shown in the various figures of the drawing, and this shaft, as before stated, operates the feeding and cutting off mechanism, one ticket being 80 cut off and another fed forward for each revolution of the shaft 16. The cam 44, therefore, rotates once for each feeding and cutting operation. In Fig. 5 the cam wheel 44 and lever 42 are shown in their normal positions in full lines, with the end 42^a of the lever close to the detent 40, and the end 42^b on a low portion of the cam wheel. As soon as the coin balance is tilted by a coin so as to move the detent out of engagement 85 with the fan, the motor starts into operation and turns the cam-wheel in the direction indicated by the arrow in Fig. 5. This causes the cam 44 to rock the lever 42 and force the end 42^a of the latter under the detent as indicated in dotted lines in Fig. 5 and in full lines in Fig. 8. This will prevent the detent from again engaging the cam until the cam 44 has made a complete revolution, 90 when the low portion of the cam will again 95 be brought opposite the end 42^b of the lever and the spring 45 will rock the lever so as to draw its end 42^a from beneath the detent. If the coin has by that time been released from the coin balance the latter will rock 100 into its normal horizontal position shown in Fig. 6, and move the detent into position to be engaged by the fan, thus stopping the motor.

I provide means whereby a coin of one denomination, as for instance a five-cent piece, dropped onto the coin balance will be released therefrom while the cam shaft 16 is making one revolution, so that for a coin of a given value one ticket will be delivered and 110 the motor will then stop, but where a coin of higher value is inserted in the machine the coin balance and detent will not be released during the first revolution of the cam shaft, and a number of tickets proportioned 115 to the value of the coin will be cut off and delivered. The machine shown in the drawing is adapted to make one complete cycle of operations when a coin of one value is inserted in the machine and to make two complete 120 cycles of operation when a coin of double the value is placed in the machine, but it will be apparent from the drawing and the following description that by increasing the number of coin retainers and 125 130

operating them in succession, the number of tickets cut off and delivered by the insertion of a single coin may be correspondingly increased. In Figs. 6 and 7 X and V indicate the lower ends of coin chutes for delivering coins of different denominations into the different parts of the coin receptacle. In my Patent No. 841,210, and also in my allowed application, Serial No. 332,598, I have 10 shown a system of chutes for assorting coins placed in a common slot in the casing of a vending machine so that coins of one denomination will pass through one chute and those of another denomination will pass 15 through another chute and in practice I use such coin assorting means in connection with the vending machine here shown. With such a system of chutes a coin of one denomination will pass through the chute 20 V and land on the free end of the coin balance, while a coin of higher denomination will pass through the chute X and land on an intermediate part of the coin balance.

When the coin balance is depressed by a 25 coin, the motor is started into operation as previously described and it is then desirable to prevent another coin from entering the coin receptacle until the motor has operated to cut off one ticket and feed another ticket 30 forward. I, therefore, provide a movable plate or shutter 46, which is hinged to the top of the side 36 of the coin receptacle, and forms a continuation of said side, and this plate normally rests against a stop 47, when 35 the motor is stopped, as shown in Fig. 2, leaving the top of the receptacle open, but as soon as the motor starts into operation the plate or shutter is automatically drawn over into the position shown in Fig. 3 so as to close 40 the top of the coin receptacle until one cycle of operation is completed, when, just before the motor comes to a stop, the plate or shutter is again moved to open position. It will be noted from an inspection of Figs. 2 and 3 45 that the lower ends of the coin chutes for delivering coins into the receptacle are inclined so that if a coin suitable for operating the machine should be inserted into the machine while the motor is in operation and the shutter 50 closed, the coin will pass through the chute X or V, as the case may be, and drop into a return chute R' which will conduct the coin to the outside of the casing of the machine, as described in my co-pending application 55 above mentioned. But when the motor is stopped, the plate or shutter 46 lies in the path of the coin coming from the chutes, and therefore a coin suitable for operating the machine, passing through either chute while 60 the motor is stopped, will be deflected from its course by the plate or shutter and will be directed into the coin receptacle and onto the coin balance, after which the motor immediately starts into operation and the shutter 65 closes until one cycle of operations has been completed. This automatic closing and opening of the deflecting plate or shutter is accomplished by means of a lever 48, loosely connected at one end to the plate and pivoted at a point intermediate its ends upon a 70 suitable standard 48^a. A spring 49, connected to the short arm 48^b of the lever normally tends to move the lever into position to close the shutter, as shown in Fig. 3, but when the motor is stopped this short arm of 75 the lever rests upon a cam or pin 50 which rotates with the cam shaft 16, the shutter thus being held open and the spring 49 being held under tension, ready to cause the closing 80 of the shutter as soon as the motor starts into 85 operation and the shorter arm of the lever is released from the pin 50. Figs. 2 and 3 show the lever and shutter in the successive positions. It will be seen that when the cam shaft and pin 50 have made a complete revolution in the direction indicated by the arrow in Fig. 8, the pin will again engage and lift the shorter arm of the lever, thus rocking the latter to open the shutter or deflecting plate 90 at about the time when the motor comes to a stop, or has completed one cycle of operations.

Coins of the value of one ticket enter the coin receptacle through the chute V. A coin entering through said chute passes onto 95 the free end of the coin balance and the latter is depressed thereby into the position indicated by dotted lines in Fig. 6 and in full lines in Fig. 7. The coin then rests upon the free end of the lever and against the vertically movable coin retaining slide v, having an arm 51, extending across the open end of the receptacle. In Fig. 7 the dotted circle d indicates a coin in this position. The coin retaining slide v is pivoted at its lower end to 100 a cam lever 52, which latter is suitably pivoted between its ends upon a post 53, as shown shown in Fig. 8. A spring 54 is provided for pulling the free end of the cam lever 52 downward and thus raising the retaining slide v; 110 but normally when the motor is stopped the free end of the cam lever is held in raised position, and the retaining slide in its lower position, by a cam 55 upon the upper side of a cam wheel E which is carried by the cam 115 shaft 16 as shown in Fig. 2.

When a coin of the value of a single ticket such as a five cent piece, passes onto the free end of the coin balance from the chute V it will lodge temporarily against the arm 51 of the coin retainer v. The motor starts by reason of the tilting of the coin balance and the consequent movement of the detent 40 out of engagement with the fan governor 13, and the free end of the locking lever 42 120 is forced by the cam wheel 44 under the detent. The free end of the cam lever 52 then trips off of the cam surface 55 and the spring 54 pulls down the free end of the lever, thus 125 causing the coin retaining slide v to move up- 130

ward and allow the coin to roll off of the coin balance and out of the coin receiver into a hopper 56 leading to the cash drawer of the vending machine. Immediately after the 5 starting of the motor the free end of the cam lever 48 also drops off the pin 50 upon the cam wheel E and the spring 49 moves said lever to close the deflecting plate or shutter, as previously explained, to prevent another 10 coin from passing into the coin receptacle while the motor is in operation. After the coin has been released from the coin balance and has dropped out of the receptacle, the coin balance and detent are prevented from 15 returning to their normal positions to stop the motor by the locking lever 42, the free end of which is then under the detent. The purpose of the coin retaining slide v is to hold the coin upon the balance long enough after 20 the motor has started to permit the locking lever to move under the detent.

Before the cam shaft 16, which operates the feeding and cutting off mechanism finishes its revolution, the cam 55 moves under 25 the free end of the cam lever 52 and thus causes the coin retaining slide v to move downward to normal position. After the coin slide v has returned to normal position, the cam or pin 50 moves the lever 48 to open 30 the deflector plate or shutter 46, and then the motor comes to a stop by reason of the free end of the locking lever 42 passing from the high circular part of the cam wheel 44 onto the lower part of said wheel. This 35 movement of the locking lever causes the release of the detent 40 which in turn is moved to its normal position in engagement with the fan by the weighted coin balance which swings into its normal position.

40 When a coin of the value of two tickets, as for instance a dime, is inserted in the machine, it passes through the chute X onto the coin balance, and in order to cut off and deliver two tickets means are provided whereby 45 by the motor is not stopped after its first cycle of operations but continues its movement until two tickets are cut off and fed forward. This is accomplished by providing an additional coin retaining slide x, which 50 practically divides the coin receptacle above the balance into two compartments h and h'. As shown in the drawings the slide x is movable vertically in suitable guides 57 upon the side 35 of the coin receptacle and it has at its 55 upper end a right angled stop 58 which projects through a vertical slot 59 in the side 35, into the receptacle above the coin balance. The slide x is connected to a cam lever 60 which is suitably pivoted between its ends 60 upon a standard 53 and the free end 60a of this cam lever extends beneath the cam wheel E, as shown in Fig. 2, in position to be engaged by a cam surface 61. Normally the cam lever 60 does not engage the cam surface and therefore the coin retaining slide x

normally rests in its lowermost position by reason of its own weight.

Assuming that a coin of the value of two tickets enters the chute X while the motor is stopped, the operation is as follows: The 70 coin balance is tilted by the coin into the position indicated in dotted lines in Fig. 6, and the coin is held upon the central portion of the balance by the shoulder 58 on the slide x. The motor then operates as previously described, the locking lever 42 first passing under the detent 40, and the shutter 46 moving to closed position. The retaining slide v is then moved upward and allowed to drop back, but during this first upward and 75 downward movement performs no function, as there is no coin on the free end of the coin balance for it to release. Near the end of the first revolution of the shaft 16 the cam surface 61 engages the end 60a of the lever 60 and the latter is rocked so as to move the slide x upward as shown in Fig. 7, thus releasing the coin d from the primary compartment of the coin receptacle and permitting it to roll down against the retainer v, as shown in dotted lines in said figure. Before the shaft 16 completes one revolution the cam 61 passes by the free end of the lever 60, thus permitting the coin retaining slide x to return to its normal position. As the 90 coin balance, at the end of one complete revolution of the cam shaft 16, is still held down by the coin, which now rests against the retainer v, the detent 40, connected to the coin balance, cannot move back to its 95 normal position and engage the fan when the locking lever 42 moves out from under it at the end of the first revolution of the shaft. Therefore the motor continues in operation, the locking lever being moved under the 100 detent during the first part of the second rotation of the shaft 16, and the coin is then released from the secondary compartment of the coin receptacle by the movement of the retaining slide v. The deflecting plate or 105 shutter 46 opens at the end of the first rotation of the cam shaft 16, and immediately closes at the commencement of the second rotation. During this second rotation the coin slide x is lifted and then released, performing no function, and at the end of the 110 second rotation of the shaft the deflecting plate or shutter moves to open position and then the locking lever 42 becomes disengaged from the detent 40, thus permitting 115 the coin balance to move to normal position and drop the detent into engagement with the fan governor, thus stopping the motor.

It will be seen that the two coin retaining slides are always in position to retain a coin, 120 when the motor is stopped, and that if a coin is inserted in the primary compartment of the coin receiver, it will not be released from the coin balance until the machine has started upon its second cycle of operations, 125 130

so that two tickets will be cut off; whereas if the coin is dropped into the secondary compartment, from the coin chute V, it will be released before the machine has completed 5 its first cycle of operations, and therefore only one ticket will be cut off. In practice, as stated, by means of suitable coin assorting chutes, coins of the value of one ticket will pass through the chute V into the secondary 10 compartment of the receiver, and coins of the value of two tickets will pass into the primary compartment. By simply lengthening the coin balance and providing a greater number of retainers arranged to operate successively, it will be evident that the machine 15 may be made to operate as many times as is desirable in order to deliver tickets corresponding in number to the value of the coin.

20 **What I claim is—**

1. In a coin-operated vending machine, a motor, a coin balance, means operated by the coin balance for releasing and stopping the motor, a chute for delivering coins onto said 25 balance, a device normally arranged to direct coins from the chute on to the balance, and means operated by the motor for moving said device into position to permit coins to pass from the chute without engaging the 30 balance while the motor is in operation.

2. In a coin operated vending machine, a motor, a coin balance, means operated by the coin balance for releasing and stopping the motor, a chute for delivering coins onto 35 said balance, a deflector normally in the path of coins passing from the chute and adapted to direct coins onto the balance, and means, operated by the motor for moving said deflector out of the path of the coins after the 40 motor has started into operation.

3. In a coin operated vending machine, a motor, a coin balance, means operated by the coin balance for releasing and stopping the motor, a chute for delivering coins onto 45 said balance, a deflector normally in the path of coins passing from the chute and adapted to direct coins onto the balance, means operated by the motor for moving said deflector out of the path of the coins after the motor 50 has started into operation, and a chute arranged to receive coins passing from said first mentioned chute while the deflector plate is out of the path of the coins.

4. In a coin-operated vending machine, a 55 motor, a stationary coin receptacle, a coin balance movable within the receptacle, means operated by the coin balance for releasing and stopping the motor, a chute for delivering coins into said receptacle, a hinged 60 deflector at the upper part of said receptacle, and means for holding said deflector in the path of coins passing from the chute while the motor is stopped and for moving said deflector out of said path when the motor is 65 in operation.

5. In a coin-operated vending machine, a motor, a stationary coin receptacle, a coin balance movable within the receptacle, means operated by the coin balance for releasing and stopping the motor, a plurality 70 of coin retainers supported independently of the balance for retaining a coin upon different portions of the balance, and means operated by the motor for moving said retainers successively to release the coin. 75

6. In a coin operated vending machine, a coin balance, means operated by the balance for releasing and stopping the motor, a plurality of coin retainers, supported independently of the balance, for retaining a coin on 80 different portions of the balance, and means operated by the motor for moving said retainers at intervals to release the coin from successive portions of the balance.

7. In a coin operated vending machine, a 85 motor, a coin balance, means connected with the coin balance for releasing the motor when the balance is depressed by a coin, a plurality of coin retainers supported independently of the balance for temporarily retaining a coin 90 on different portions of the balance, means operated by the motor for locking the balance in its depressed position, means operated by the motor for moving said retainers at intervals to release the coin from successive portions of the balance, and means operated by the motor for releasing the coin balance. 95

8. In a coin operated vending machine, a motor, a coin balance, means connected 100 with the coin balance for releasing the motor when the balance is depressed by a coin, a plurality of coin retainers supported independently of the balance for temporarily retaining a coin on different portions of the balance, means operated by the motor for locking the balance in its depressed position, means operated by the motor for moving said retainers successively to release the coin, 105 and means operated by the motor for releasing the coin balance. 110

9. In a coin operated vending machine, a stationary coin receptacle, open at one end, a pivoted coin balance fitting between the sides of said receptacle and extending from its 115 pivotal point toward said open end, a coin retaining slide having a part extending across the receptacle at its open end, a second coin retaining slide extending over the balance between its free end and its pivotal point, 120 said slides being each supported independently of the balance and normally in position to retain a coin on the balance, means connected with the coin balance for releasing the motor when the balance is depressed by coin, 125 and means operated by the motor for moving said retainers successively.

10. In a coin operated vending machine, a motor, a stationary coin receptacle, a coin balance therein, two coin retainers supported 130

independently of the balance and adapted to retain a coin on different portions of the balance, means operated by the coin balance for releasing the motor when the balance is depressed and for stopping the motor when the balance moves to normal position, means operated by the motor for locking the coin balance in its depressed position and for releasing the balance after the motor has made 10 a given movement, and means operated by the motor for moving said coin retainers alternately.

11. In a coin operated vending machine, a motor, a stationary coin receptacle, a coin balance therein, two coin retainers supported independently of the balance and adapted to retain a coin on different portions of the balance, means operated by the coin balance for releasing the motor when the balance is depressed and for stopping the motor when the balance moves to normal position, a device 15 for locking the coin balance, a cam operated by the motor for moving said device to lock

and release the balance, and means operated by the motor for moving said coin retainers 25 alternately.

12. In a coin operated vending machine, a motor, a stationary coin receptacle, a coin balance therein, two coin retainers supported independently of the balance and adapted to 30 retain a coin on different portions of the balance, means operated by the coin balance for releasing the motor when the balance is depressed and for stopping the motor when the balance moves to normal position, a lever for locking and releasing the coin balance, levers 35 for moving said coin retainers, and a cam shaft having cams thereon and driven by the motor for operating said levers.

In testimony whereof I affix my signature, 40 in presence of two witnesses.

GEORGE C. YOCUM.
